UNITED STATES PATENT OFFICE.

JAMES WILLIAM WHALEN AND CORNEALIUS J. McLAUGHLIN, OF TEKOA, WASHINGTON.

WASHING-MACHINE.

1,193,328.

Specification of Letters Patent. Patented Aug. 1, 1916.

Application filed November 20, 1915. Serial No. 62,514.

To all whom it may concern:

Be it known that we, JAMES WILLIAM WHALEN and CORNEALIUS J. McLAUGHLIN, citizens of the United States, residing at 5 Tekoa, in the county of Whitman and State of Washington, have invented certain new and useful Improvements in Washing-Machines; and we do hereby declare the following to be a full, clear, and exact description of the invention, such as will enable others skilled in the art to which it appertains to make and use the same.

Our invention relates to new and useful improvements in washing machines and our 15 object is to provide a receptacle and mount the same upon a frame in such position that it may be tilted or rocked to move the contents of the receptacle from end to end thereof.

20 A further object is to provide baffle plates at the ends of the receptacle and so arrange the same that air and water will be forced through the garments within the receptacle.

25 A further object is to provide spring means for assisting in the rocking action of the receptacle.

A further object is to provide means whereby the receptacle may be transported 30 from place to place.

A further object is to provide means for attaching a wringer to the receptacle. And a further object is to provide means for reinforcing the ends of the receptacle.

35 Other objects and advantages will be hereinafter set forth and more particularly pointed out in the accompanying specification.

In the accompanying drawings which are 40 made a part of this application, Figure 1 is a top plan view of the washing machine ready for use. Fig. 2 is a longitudinal sectional view therethrough, and Fig. 3 is a detail sectional view, as seen on line 3—3 45 of Fig. 2.

Referring to the drawings in which similar reference numerals designate corresponding parts throughout the several views, 1 indicates a frame structure, preferably constructed of wood and having standards 2 on opposite sides thereof and substantially at its longitudinal center, said frame also having end posts 3 and 4 between which and the standards 2 is positioned a receptacle 5, preferably rectangular in general outline.

Each side of the receptacle 5 is provided with a trunnion 6 which engages a notch 7 in the upper end of each standard 2, said trunnions being at the longitudinal center of the receptacle so that said receptacle may be rocked to move the contents of the receptacle from end to end thereof. The bottom 8 of the receptacle is preferably corrugated so that the garments and water within the receptacle will be thoroughly agitated in passing from end to end of the receptacle, and in order to cause air to pass through the garments and thus thoroughly cleanse the same, a plurality of baffle plates 9 are placed at each end of the receptacle, said baffle plates being spaced a predetermined distance apart and inclined downwardly from their outer to their inner edges, each baffle plate preferably having a plurality of perforations 10 for the passage of the air confined between the baffle plates, thus causing the air to percolate through the garment with more or less force as the water within the receptacle forces the air from between the baffle plates. The receptacle 5 is provided with handles 11 which are positioned at the ends of the receptacle and adjacent the upper edge thereof so that said handles may be readily grasped to give rocking motion to the receptacle.

In order to facilitate the rocking action of the receptacle, a spring 12 is attached to the lower bar of the frame 1 in any suitable manner, the upper end thereof extending through a block 13 of a bolt 14, said bolt 90 being rotatably mounted in a socket 15 which socket is in turn attached to the bottom of the receptacle. The spring 12 is slidably mounted through the block 13 while the bolt 14 is pivotally arranged in 95 the socket 15 so that the upper end of the spring may be swung laterally as the receptacle 5 is rocked on the trunnions 6, the tension of the spring being directed against the receptacle in such manner as to aid the 100 rocking of the receptacle.

The body of the receptacle is preferably made of sheet metal, while the top portion 16 is preferably constructed of wood, said top having an opening 17 therethrough 105 which is normally closed by a cover or lid 18, said cover being held in position over the opening in any preferred manner. Positioned adjacent one end of the opening 17 and secured to the top 16 in any preferred 110

manner is a bar 19 having brace members 20, said bar being designed to receive any suitable form of wringer (not shown).

In order to reinforce the walls of the receptacle 5 and form a more rigid structure, brace straps 21 are extended below the ends of the receptacle and part way up the sides thereof, said straps being formed of metal of sufficient rigidity to properly brace the receptacle and form a more or less rigid structure. The receptacle is provided at one end with a drain pipe which is normally closed by a cap 23, while the end posts 3 and 4 have brackets 24 attached thereto to form 10 a rest for a wash boiler or similar article, while the garments are being entered into the receptacle or removed therefrom.

The post 3 terminates in line with the lower bar of the frame 1 and a shaft 25 is 20 extended transversely of the frame and below the ends of the post 3, said shafts having supporting wheels 26 at the ends thereof, by means of which the washing machine may be transported from place to place, the 25 post 4 extending beyond the frame 1 and forming a rest for that end of the frame when the machine is in use. The upper cross bar of the frame 1 is extended beyond the end posts 4 and the extended portions are formed into handle bars 27 which 30 are to be grasped when the machine is being moved from place to place.

In operation, the garments with a predetermined amount of water are placed 35 within the receptacle 5 and the cover secured thereover when the operator directs downward or upward pressure on one of the handles 11 thereby tilting the receptacle and causing the garments to pass to the 40 lowered end of the receptacle and engage the edges of the baffle plates at that end with force, and in view of the inclination of the baffle plates the garments will lap over the edges and upper faces thereof so that the 45 air confined between the baffle plates will be forced through the garments, and in view of the inclination of the baffle plates, the garments will readily leave the same when the receptacle is tilted in the opposite direction.

50 As the end of the spring 12 is brought into

operation with the tilting of the receptacle, causing a tension thereon, said tension will be employed for returning the receptacle to its initial position, thus requiring but a minimum amount of strength to keep the 55 receptacle in rocking motion.

After the garments have been properly cleansed, the cover 18 may be removed and a wringer attached to the bar 19 and the garments passed through the wringer for 60 squeezing the water therefrom, and in view of the position of the wringer, the water will descend into the receptacle as it is removed from the garments by the wringer. The water within the receptacle may then 65 be removed by removing the cap 23 from the drain pipe 22 and by tilting the end of the receptacle having the drain pipe downwardly, the entire contents of the receptacle may be removed through the drain 70 pipe.

It will likewise be understood that the frame structure and spring feature may be used in connection with a churn body for supporting and rocking the same, the same 75 action being accomplished with one as with the other.

Having thus fully described our invention what we claim as new and desire to secure by Letters Patent of the United States, is:— 80

A washing machine, the combination with a frame and a receptacle pivotally mounted thereon, of a spring having one of its ends attached to said frame, a bolt pivotally secured to the receptacle, said bolt having a 85 block through which the opposite end of the spring extends, said spring being at the longitudinal center of the receptacle whereby when the receptacle is rocked, the tension of the spring will be increased and the rocking movement of the receptacle facilitated 90 by the tension of the spring.

In testimony whereof we have signed our names to this specification in the presence of two subscribing witnesses.

JAMES WILLIAM WHALEN.
CORNEALIUS J. McLAUGHLIN.
